ADJUSTABLE TRUSS

Jerome De Mott, Long Island City, N. Y., assignor
to Watkins Surgical Corporation, New York,
N. Y., a corporation of Delaware

Application July 21, 1952, Serial No. 300,025

3 Claims. (Cl. 128—105)

1

This invention relates to a truss for supporting and retaining muscles in apposition in cases of hernia.

An object of the invention is to provide a truss in which a pad for supporting muscles is constructed in a manner to permit of the convenient insertion therein of soft compressible filler elements so as to afford the required support and which are removable and replaceable as required.

Still another object of the invention is to provide a truss in which the pad is provided with a resilient backing adapted to engage over one end of a bowed spring member for fastening the truss in position on the body of the wearer and which backing is expandable to permit of the insertion of a rigid supporting member and the required number of filler elements.

Still another object of the invention is to provide a truss of said character in which the bowed spring member is formed with a coiled end for supporting the pad about the periphery thereof whereby the central portion of the pad is adapted to provide the proper resilient support for the focal area of the hernia.

Still another object of the invention is to provide a truss which is highly efficient, simple in structure and which is comfortable to the wearer.

With the foregoing and other objects in view, reference is now made to the following specification and accompanying drawings in which the preferred embodiment of the invention is illustrated.

In the drawings:

Fig. 1 is a plan view of a truss constructed in accordance with the invention.

Fig. 2 is a side view thereof.

Fig. 3 is a fragmentary sectional view taken approximately on line 3—3 of Fig. 1.

Fig. 4 is an enlarged sectional view taken approximately on line 4—4 of Fig. 1.

Fig. 5 is a similar view with one of the filler elements removed.

Referring to the drawings by characters of reference, the truss consists of a resilient longitudinally bowed member 10 having a terminal end 11 of looped formation and a terminal end 12 of circular formation to which a soft compressible cushion or pad 13 is removably attached. The bowed member 10 is preferably fashioned of a spring wire 14 to provide the necessary resiliency for engagement about a portion of the human body with the cushion or pad 13 disposed in overlying tensioned relation against the muscles at the focal area of the hernia or rupture and with the terminal end 11 resiliently engaging

against the portion of the human body opposite the hernia or rupture. The spring wire 14 is disposed within a soft flexible rubber tube 15 which extends continuously about the terminal ends 11 and 12. The looped portion forming the terminal end 11 extends through a relatively larger soft compressible rubber tube 16 which has limited area to contact with the body of the wearer so as to prevent undue heating thereof and which by its resiliency and compressibility provides a comfortable engagement with the body of the wearer.

The circular portion forming the terminal end 12 is disposed in a plane substantially parallel with the plane of the terminal end 11 and is integrally connected with the bowed member 10 by a coiled portion 17 which increases in size inwardly toward the terminal end 12. The cushion or pad 13 is supported by the terminal end 12 adjacent the outer periphery thereof with the coiled portion 17 permitting of the flexing of the cushion or pad 13 annularly about the center through the pad and coil as indicated by the broken line 18. The cushion or pad 13 includes a soft compressible wall 19 formed of felt or equivalent soft material which is adapted to engage against the body of the wearer in the region of the hernia or rupture and to which is secured a backing 20 by stitching or equivalent fastening means 21 extending continuously about the wall 19 adjacent the periphery thereof. The backing 20 is of flexible elastic material which is adapted to stretch for resiliently engaging over the terminal end 12 for mounting the cushion or pad on the bowed member 10. The backing 20 is formed with a central opening 22 which is adapted to be expanded for inserting the terminal end 12 in position between the backing and the wall 19. A relatively stiff member 23 is supported on the terminal end 12 and between the stiff member 23 and the inner face of the wall 19 a pocket 24 is provided for receiving one or more soft compressible filler elements for supporting the wall 19 in bowed relation in cross-section whereby the cushion or pad provides the greatest support at the focal area or center area of the hernia or rupture. As illustrated in Fig. 4 of the drawings, two such filler elements 25 and 26 are provided in the pocket 24, the filler element 26 being smaller than the filler element 25 while in Fig. 5 of the drawings a single filler element 27 is provided.

In order to retain the truss in position, an adjustable strap or band 28 is provided which is looped about the terminal end 11 to secure the same thereto and is provided with a metal hook

30 which is adapted to engage the outermost loop of the coil portion 16 for securing the same to the terminal end 12. The strap or band 29 is looped through a metal hook 30 with the doubled-over end thereof provided with a slide 31 through which the strap or band extends for adjusting the length thereof. The strap or band engages about the body of the wearer in opposite relation from the bowed member 10 so as to secure the bowed member 10 in position and prevent displacement of the cushion or pad 13.

What is claimed is:

1. In a truss, a resilient longitudinally bowed member having oppositely disposed enlarged terminal ends, one of said terminal ends being offset inwardly and of circular formation, a soft compressible pad having an elastic backing secured thereto adjacent the edge thereof and provided with an opening, said bowed member extending through said opening with the inwardly offset terminal end disposed between the backing and the pad and stretching the backing for securing the pad on said terminal end, a supporting member positioned on said offset terminal end, and said pad and backing providing a pocket for receiving a soft compressible filler element between the pad and the supporting member, and an adjustable band connected at its opposite ends to said terminal ends and adapted to engage about the body of the wearer opposite the bowed member for securing the bowed member in position on the wearer with the pad disposed in tensioned engagement against the body of the wearer.

2. In a truss, a resilient longitudinally bowed member having oppositely disposed enlarged terminal ends, one of said terminal ends being offset inwardly and of circular formation and connected with the bowed member by a helical coiled portion to provide resiliency for said bowed portion, a soft compressible pad having an elastic backing secured thereto continuously about the edge portion thereof and providing an opening, 10 said bowed member extending through said opening with the inwardly offset terminal end disposed in tensioned relation between the backing and the pad for securing the pad to said terminal end, a supporting member positioned on said offset terminal end and said pad and backing providing a pocket for receiving one or more soft compressible filler elements between the pad and the supporting member, and an adjustable band connected at its opposite ends to said terminal 15 ends and adapted to engage about the body of the wearer opposite the bowed member for securing the bowed member in position on the wearer with the pad disposed in tensioned engagement against the body of the wearer.
